CLAIM

The ornamental design for a valve for an aerosol container, as shown and described.

DESCRIPTION

FIG. 1 is a perspective view of a valve for an aerosol container, showing our new design;
FIG. 2 is a front side elevation view thereof;
FIG. 3 is a rear side elevation view thereof;
FIG. 4 is a right elevation view thereof;
FIG. 5 is a left elevation view thereof;
FIG. 6 is a top plan view thereof; and,
FIG. 7 is a bottom plan view thereof.

In the drawings, the broken lines show portions of a valve for an aerosol container that form no part of the claim.
